UNITED STATES PATENT OFFICE

WILLIAM HENRY KANE KING, OF MOUNT STERLING, ILLINOIS.

TABLET.

SPECIFICATION forming part of Letters Patent No. 337,503, dated March 9, 1886.

Application filed July 17, 1885. Serial No. 171,875. (No model.)

To all whom it may concern:

Be it known that I, WILLIAM HENRY KANE KING, of Mount Sterling, in the county of Brown and State of Illinois, have invented an 5 Improved Tablet, of which the following is a specification.

The invention will first be described in connection with the drawings, and then pointed out in the claims.

10 Figure 1 of the drawings is a plan view. Fig. 2 is a longitudinal central section; Fig. 3, a transverse vertical section axially through one of the rollers, as well as through side pieces and supports. Fig. 4 is a detail 15 view in perspective of the shield.

In the drawings, A represents my tablet in its entirety. It has the plate or board a, supported in the two parallel side pieces, a' a', and the parallel end rollers, a² a², journaled in 20 the four corner-supports a³ a³ a³ a³. Each of the rollers is provided with a longitudinal keeper or wire, a⁴, under which the ends of paper may be secured, or the rollers may be slotted for the same purpose, or any other 25 suitable way of fastening the paper to the rolls may be adopted. Each roller a² is provided with an outside knob or crank, so that it may be turned with the hand in order to transfer the roll of paper partially or entirely 30 from one roll to the other.

For the purpose of avoiding all noise, in school or elsewhere, from the turning of the rolls, I use an elastic bearing, B, provided with a right-angled flange adapted to serve 35 for a bearing and a washer, the latter coming between the shoulder of the roll and the corner-supports a³. The side pieces have graduated scales upon their upper edges, for the

purpose of measuring distances and to assist in map or other drawing. 40

C represent shields detachably arranged under elastic bands D D, which pass over the curved bottoms of the supports a³. These shields are corner-notched at e, so as to pass down on the inside below the fasteners E E, 45 which hold bands D to the supports a³. They are thus prevented from lateral displacement.

The bands D are made to perform two functions, namely: to confine the shields and to deaden the noise which children make in 50 moving the tablet.

By notching the shields at the corners and end-fastening rubber straps across the bottom of the bearing-blocks the shields may be easily removed by simply turning back the 55 rubber.

Having thus described all that is necessary to a full understanding of my invention, what I claim as new, and desire to protect by Letters Patent, is— 60

1. The two parallel end rollers, a² a², having keepers a⁴ and outside knobs, in combination with two parallel side pieces, a' a', four corner-supports, a³, the shields C, and elastic bands D, all arranged substantially as shown 65 and described.

2. In a tablet, the combination, with the rolls and bearing-blocks, of shields notched at the corners and rubber straps end-fastened across the bottom of said blocks, whereby the 70 shields may be easily removed by turning back the rubber.

WILLIAM HENRY KANE KING.
